UNITED STATES PATENT OFFICE.

FRANK R. BODNAR, OF BRIDGEPORT, CONNECTICUT.

WINDOW-SASH LOCK.

Application filed April 1, 1922. Serial No. 548,621.

To all whom it may concern:

Be it known that I, FRANK R. BODNAR, a citizen of the United States, and a resident of Bridgeport, in the county of Fairfield and State of Connecticut, have invented certain new and useful Improvements in Window-Sash Locks, of which the following is a specification.

This invention pertains to a small and simple device for ready attachment to a window sash for locking together two sliding sashes to prevent their unauthorized opening from the outside of the window.

The object of this invention is to provide a device of this character that can be readily attached to any window sash rail, and without tools, and which can be swung to engaging position with the other sash, and also locked in such position if desired, and which can be swung back to an inoperative position.

A further object of the invention is to provide in a device of this character a base member and lever member, and which lever member is provided with a cam member for engagement with the window sash.

A further object of the invention is to provide in connection with said device, locking means between the lever and base member to hold the lever member in the locking position.

In the accompanying drawing showing one embodiment of the present invention, Fig. 1 shows the device in locking position on a window sash.

Fig. 2 is a side elevation of the same being in section through the window sash.

Fig. 3 shows the several parts in separated position, ready for assembling.

The device comprises essentially a base plate, a lever plate hinged to the base plate, and a cam rotatable on the free end of the lever plate.

As shown in the drawing I provide a base plate 1, having a bent ear 2, on one end to form a hinge. A lever plate 3 is provided with bent ears 4, 4, at one end between which the bent ear 2 is inserted, and the two members hinged together by means of a pin 8.

The base member is also provided with several prongs 14 that may be integral pointed ears extending downwardly by means of which this plate can be readily attached to the sash rail 15 of the window, by merely using a few hammer blows. This base plate is also shown provided with an integral arm

11 suitably apertured, that will project through a slot 12 in the lever plate 3, and a cotter pin 13 passed through the apertured ear will act to prevent swinging movement of the plate 3 away from the plate 11 as indicated in Fig. 2.

On the further end of the lever plate 3 are ears 5, 5, separated by a slot 16. These ears 5 receive a pin 7 on which a cam member 6 is rotatable in the slot 16, as indicated in Fig. 2. This cam is provided with a tooth portion 9, and an enlarged or cam portion 10 whose ends form prongs 17, 18. The tooth portion can swing in the slot 16, but the larger portion 10 will strike the plate or the end of the slot and prevent turning of the cam, from the position shown in Fig. 2.

In the use of the device, the base plate 1 is placed on the sash rail 15, and the prongs 14 are driven in to securely hold the base plate on the sash rail, see Fig. 2, during which operation the lever plate 3 is swung forward away from the upper sash. Then this plate is swung over against the other sash and will engage the side rail 19 by the tooth portion 9. The two sashes are shown in the closed position, and if the lower sash is raised or the upper sash is lowered as indicated in Fig. 1, the cam will be rotated and bring the portion 10 against the rail 19 that will lock it in this position and prevent further separation of the sashes in this direction. If desired, the cotter pin 13 can now be placed through the apertured ear 11 that will lock the lever plate in this position until it is again desired to loosen the two sashes. When one of the sashes are turned to their former position the cam will be rotated in the opposite direction, and the cotter pin being withdrawn will free the sashes.

A device of this kind is comparatively simple and cheap to manufacture and easy to attach and operate.

What I claim is:

1. A window lock comprising a base plate having attaching means, a lever plate hinged to one end of the base plate, and a cam wheel eccentrically pivoted on the free end of the lever plate with its axis parallel with the lever axis.

2. A window lock comprising a base plate having attaching means, a lever plate hinged to one end of the base plate, and a cam wheel pivoted on the free end of the lever plate with its axis parallel with the

lever axis, the said two plates having locking means comprising an apertured ear on one plate adapted to project through a slot in the other plate, and a key or fastener projecting through said apertured ear.

3. A window lock comprising a base plate having attaching means, a lever plate hinged to one end of the base plate, a cam wheel pivoted on the free end of the lever plate with its axis parallel with the lever axis, said cam wheel having a portion of its periphery provided with teeth and a cam portion of greater radius than the tooth portion.

15 4. A window lock comprising a base plate having attaching means, a lever plate hinged to one end of the base plate, and a cam wheel pivoted on the free end of the lever plate with its axis parallel with the lever axis, the said lever plate having a slot, an apertured integral ear on the base plate adapted to project through a slot in the other plate, and a key or fastener projecting through said apertured ear.

20 25 5. A window lock comprising a base plate having attaching means, a lever plate hinged to one end of the base plate, and a cam wheel pivoted on the free end of the

lever plate with its axis parallel with the lever axis, the lever plate having a slot at its free end in which the cam wheel turns.

6. A window lock comprising a base plate having attaching means, a lever plate hinged to one end of the base plate, a cam wheel pivoted on the free end of the lever plate with its axis parallel with the lever axis, said cam wheel having a portion of its periphery provided with teeth and a cam portion of greater radius than the tooth portion, the lever plate having a slot at its free end in which the cam wheel turns, and which forms a stop for the cam portion beyond the teeth.

7. A window lock comprising a base plate having attaching means, a lever plate hinged to one end of the base plate, a cam wheel pivoted on the free end of the lever plate with its axis parallel with the lever axis, said cam wheel having a portion of its periphery provided with teeth and a cam portion of greater radius than the tooth portion, one end of which is pointed to engage the window.

Signed at Bridgeport, Conn., on March 29, 1922.

FRANK R. BODNAR.
